[57] CLAIM

The ornamental design for the covered serving dish or the like, as shown and described.

DESCRIPTION

FIG. 1 is a top perspective view of the covered serving dish or the like showing our new design;
FIG. 2 is a top plan view thereof;
FIG. 3 is a bottom plan view thereof;
FIG. 4 is a side elevational view thereof;
FIG. 5 is an end elevational view thereof;
FIG. 6 is a cross-sectional view taken along line 6—6 of FIG. 2; and
FIG. 7 is an exploded top perspective view thereof.
